ELECTRIC FIXTURE

Alphonse F. Pieper, Brighton, N. Y.

Application May 8, 1940, Serial No. 334,023

4 Claims. (Cl. 240—81)

This invention relates to an electric fixture, with more particular reference to the general type of lamp construction disclosed in application Serial No. 324,535, filed March 18, 1940, employing elongated lighting elements such as fluorescent tubes, and has for its purpose to afford a practical and efficient structure adapted to supporting such lighting elements in a lamp or other fixture.

10 A further object of the invention is to provide a construction of few parts and simple design, in which a multiplicity of elongated light elements can be rigidly supported in various intersecting vertical planes and each inclined to the horizontal, affording a strong support for the light elements and facilitating the positioning or replacement of any individual light element.

Another purpose of the invention is to afford an arrangement that enables mounting all the 20 light elements on a central post located intermediate the ends of transversely extending light elements and their carrier frames, thus eliminating the necessity of a frame or other supporting means surrounding or located outside the 25 ends of the light elements, so as not to interfere with the conventional arrangement and relationship of a central lamp standard and shade supported thereon.

An additional object of the invention is to provide a structure adapted to supporting elongated light elements, and which can be manufactured at such a low cost as to place the device within the financial reach of a large number of people.

35 To these and other ends, the invention consists in the construction and arrangement of parts that will appear clearly from the following description when read in conjunction with the accompanying drawings, the novel features 40 being pointed out in the claims following the specification.

In the drawings:

Fig. 1 is a view in side elevation, the shade appearing in section, showing a lamp equipped 45 with one embodiment of the invention;

Fig. 2 is a plan view showing the relation between the supporting post and the elongated light elements;

Fig. 3 is a detail view in side elevation of one of the lighting tubes and its carrier frame;

Fig. 4 is a detail sectional view taken transversely through the supporting post and the attached tubular member of one of the carrier frames, and

Fig. 5 is a partial view in side elevation of the supporting post.

Referring more particularly to the drawings in which like reference numerals refer to the same parts throughout the several views, 1 designates a lamp base provided with a conventional switch 2 and reactors 3 from which the conductors lead upwardly through the central supporting post 4 to the light elements presently to be described.

10 The invention is shown as adapted to accommodating conventional fluorescent light tubes, although any type of elongated light element may be employed, where it is desirable to arrange the tubes or light elements transversely 15 of a central vertically arranged supporting post and preferably in inclined relation thereto.

In the structure disclosed, there are four such light elements designated at 5 and 6, and 7 and 8 respectively. The tubes 5 and 6 are arranged 20 parallel to each other on opposite sides of the supporting post 4 and in right angular relationship to the tubes 7 and 8 which are also disposed on opposite sides of the supporting post, as shown in Fig. 2. The tubes of each pair are 25 inclined in opposite directions as shown in Fig. 1, so that each tube extends over one tube of the other pair and under the other tube of the same pair, affording a symmetrical disposition of the light elements and resulting in an even 30 distribution and maximum diffusion of light.

All the light tubes are mounted upon the central supporting post 4, and to this end each tube is secured in a carrier frame, see Fig. 3, which includes a member preferably in the form of a 35 tube 9 that extends endwise of the light element and is provided at its ends with lateral extensions 10 which carry the sockets 10^a within which the light tube 8 is detachably arranged. Each carrier frame is supported on the central 40 post 4, extending transversely thereof, by attaching the tube 9 at a point between its ends rigidly to the supporting post 4.

The individual carrier frames may be attached to the supporting post in any convenient way, and in the present embodiment, this is accomplished by soldering or welding each tubular member 9 to the supporting post 4 at the desired angle of inclination. This may be accomplished by providing the post 4 with a groove or slot 11 in its periphery at the desired angle, the tube 9 being anchored in the slot 11 and rigidly attached by a soldered or welded joint.

In order to accommodate the electric conductors, the supporting post 4 is preferably made

hollow, as shown in Fig. 4, and provided with openings 12, see Fig. 5, which are coincident with openings 13 in the tubular members 9, so that the electric conductors for each light element extend from the base 1 upwardly through the post 4 and thence through the opening in the post and through the tubular member 9 to the sockets 10.

- 13^a designates a conventional shade or shield 10 surrounding the light elements and provided with a frame 14 at the top, which is supported on the upper end of the central post 4. While the invention is disclosed in conjunction with a lamp and lamp base, it will be understood 15 that the same principle may be applied to a depending supporting post forming part of a ceiling or wall fixture, in which the individual light elements are mounted on carrier frames, each carrier frame preferably extending endwise of 20 its light element and being attached to the supporting post at a point between the ends of the carrier frame.

The light elements need not necessarily be arranged in pairs as shown, but each may be located 25 in symmetrical angular relationship to the other light elements, and the carrier frames may be constructed in various ways, the essential characteristic of the invention being that each carrier frame extends transversely of the 30 supporting post and is rigidly attached at a point between its ends to the supporting post.

While the invention has been described with reference to the details of construction herein disclosed, it is not confined to this precise embodiment, and this application is intended to 35 cover such modifications or departures as may come within the purposes of the invention or the scope of the following claims.

I claim:

- 40 1. In an electric fixture, the combination with a vertically arranged hollow supporting post and an elongated light element disposed transversely with respect to said supporting post, of a tube attached at a point between its ends 45 to the supporting post, the supporting post and tube having coincident openings to receive electric conductors, and sockets at the ends of the tube for supporting the light element, the said tube having a cross-section considerably smaller than the cross-section of the light element so as 50 to offer a minimum obstruction to the rays from said light element; said tube constituting the sole means of support for the light element, and the post constituting the sole means of support 55 for said tube.

2. In an electric fixture, the combination with

a vertically arranged supporting post, of a multiplicity of elongated light elements disposed transversely of said supporting post and inclined to the horizontal, a supporting bar for each of said light elements extending endwise thereof and attached at a point between its ends to the supporting post, and sockets at the ends of each bar for supporting a light element, each of said bars having a cross-section considerably smaller than the cross-section of the light element so as 10 to offer a minimum obstruction to the rays from said light element; said bars constituting the sole means of support for the light elements, and the post constituting the sole means of support for said bars. 15

3. In an electric fixture, the combination with a vertically arranged supporting post, of a pair of elongated light elements disposed transversely of said supporting post on opposite sides thereof and inclined in opposite directions, a second pair of elongated light elements disposed on opposite sides of said supporting post and in right angular relationship to the first mentioned light elements, a supporting bar for each light element extending endwise thereof and attached 25 at a point between its ends to the supporting post, and sockets at the ends of each supporting bar for supporting a light element, the said bars having a cross-section considerably smaller than the cross-section of the light elements so as to 30 offer a minimum obstruction to the rays from said light elements; said bars constituting the sole means of support for the light elements, and the post constituting the sole means of support for said bars. 35

4. In an electric fixture, the combination with a vertically arranged hollow supporting post and a multiplicity of elongated light elements disposed in intersecting vertical planes in inclined position and on opposite sides of the supporting 40 post, of a tubular member for each light element extending endwise thereof and provided at its ends with sockets for holding the light element, each tubular member being attached between its ends to said supporting post, the supporting 45 post and tubular member having coincident openings to receive electric conductors and the tubular members having a cross-section considerably smaller than the cross-section of the light elements so as to offer a minimum obstruction to the rays from 50 said light elements; said tubular members constituting the sole means of support for the light elements, and the post constituting the sole means of support for said tubular members. 55

ALPHONSE F. PIEPER.
